2 SHEETS—SHEET 2.

UNITED STATES PATENT OFFICE.

NILS J. SODERLUND, OF MEDFORD, MASSACHUSETTS.

CEILING-WASHING MACHINE.

1,414,101.

Specification of Letters Patent Patented Apr. 25, 1922.

Application filed October 6, 1920. Serial No. 414,975.

To all whom it may concern:

Be it known that I, NILS J. SODERLUND, a citizen of the United States, residing at Medford, in the county of Middlesex and 5 State of Massachusetts, have invented certain new and useful Improvements in Ceiling-Washing Machines; and I do hereby declare the following to be a full, clear, and exact description of the invention, such as 10 will enable others skilled in the art to which it appertains to make and use the same.

This invention relates to new and useful improvements in ceiling washing machines and has for its primary object the provision 15 of a device of the above stated character which may be conveniently supported and operated by a person standing on the floor without the liability of spilling or splashing the cleaning fluid on the surrounding 20 walls or floor, and also provide a device which will efficiently clean a ceiling in a comparatively short time, and thereby provide a large saving in labor.

Another object of this invention is the 25 provision of a fluid container carrying scrubbing and fluid applying mediums which may be easily actuated by a person standing on the floor to apply the fluid to the ceiling with a thorough scrubbing action.

30 A further object of this invention is the provision of a supporting element having the fluid container so connected thereto, that the latter will be permitted to assume a perpendicular position and which will allow the 35 same to be manually lowered or moved away from the ceiling in said position without lowering the supporting element.

A still further object of this invention is the provision of a ceiling washing machine 40 of the above stated character which will be simple, durable and efficient, and which may be manufactured and sold at a comparatively low cost.

With these and other objects in view, as 45 will become more apparent as the description proceeds, the invention consists in certain novel features of construction, combination, and arrangement of parts as will be hereinafter more fully described and claimed.

50 For a complete understanding of my invention, reference is to be had to the following description and accompanying drawings, in which

Fig. 1 is a side elevation partly in section

illustrating a ceiling washing machine, constructed in accordance with my invention, 55

Fig. 2 is a top plan view of the same,

Fig. 3 is an end elevation illustrating the device,

Fig. 4 is a detail sectional view illustrating 60 the means of connecting the pole or supporting element to the container.

Fig. 5 is a detail view illustrating the means of rotating the operating rod carried 65 by the supporting element or pole.

Referring in detail to the drawings, the 70 numeral 1 indicates as an entirety a washing machine consisting of a casing 2 that includes an elongated portion 3 terminating in a reduced and downwardly depending portion 4 and said elongated portion 2 has its upper end fully open to expose a rotating brush 5 and a fluid applying roller 6. The brush and roller are mounted on shafts 7 and 8 that extend through the side walls of 75 the elongated portion 3 of the container 2 by way of slots 9. The slots 9 open outwardly through the upper edge of the container so that the brush and roller can be 80 removed when desired. The upper portions of the brush and roller project above the upper edge of the container 2 while their lower portions are submerged within cleaning fluid located within the reduced and downwardly depending portion 4 and a portion of 85 the elongated portion 2. The shafts 7 and 8 project beyond the side walls of the container 2 and are rotatably supported by brackets 10 which are adjustably mounted so that the brush may be raised and lowered in the container. The brackets are adjusted by nuts 12' threaded on the rods 13' and the latter 90 extend through slots in ears 14' of said brackets. Gears 11 and 12 are secured to the shafts 7 and 8 and mesh with gears 13 that 95 are journaled on stub shafts 14 and are in mesh with each other so that on rotation of the gear 11, the brush and roller will be rotated in opposite directions. The gear 11 has formed integrally therewith a beveled gear 15 which meshes with a pinion 16 secured to the upper end of an operating rod 17. The operating rod 17 is rotatably 100 mounted in bearings 18 carried by one of the brackets 10 and is held against endwise movement in relation to the container by said 105 bearings and is constructed from a plurality of detachable sections and is also provided

with a universal joint 18'. The rod 17 has its lower end journaled in a bracket 19 which is carried by a collar 20 splined to a supporting element or pole 21. A cross arm 22 is mounted in a bearing carried by the upper end of the pole or supporting element 21 and is held against rotation therein by means of a set screw 24. A pair of arms 25 are journaled on the cross arm 22 and are 10 in turn pivotally connected to brackets 10 of the container 2. Coil springs 26 are mounted on the cross arm 22 and have one of their ends secured thereto while the other ends bear against the arms 25 for normally 15 supporting said arms in a substantially upwardly inclined plane and which in turn supports the container 2 in a perpendicular position.

The bracket 19 has journaled thereto a 20 bevel gear 27 which meshes with a bevel gear 28 splined to the lower end of the operating rod 17 and said bevel gear 27 is provided with a suitable handle 29 whereby 25 the operating rod 17 may be rotated, which in turn rotates the roller and brush 5 in opposite directions.

A shaft 30 is journaled in the side walls of the container 2 and has secured thereon roller 31 that projects beyond the upper 30 edge of the container for engagement with the ceiling and cooperates with the roller 6 in preventing the upper edge of the container from contacting with the ceiling during the use of the device, but will permit 35 the brush 5 to have contact with the ceiling. A suitable scraper 32 is secured to the container 2 adjacent the roller 31 and is constructed from rubber or any other material suitable for the purpose and provides means 40 whereby the device can be used as a scraper for removing particles that may adhere to the ceiling.

A collar 33 is secured to the pole adjacent its lower end and has formed thereon 45 a hook 34 adapted to engage a suitable belt (not shown) for attaching the supporting pole to a person, so that said person may have his hands free to manipulate the device. A cord or flexible element 35 is secured to the lower end of the reduced portion 50 4 and received by an eyelet 36 at the lower end of the supporting pole 21 providing a construction which will permit the operator to move the container downwardly 55 in a perpendicular path and away from the ceiling without lowering the supporting pole 21. The pole 21 includes a plurality of detachable sections which will permit of the pole being shortened when desired and also 60 to be taken apart when storing the device.

In operation, a person standing on the floor supports the pole 21 by means of the hooks 34 engaging a belt worn by the person and the rollers 31 and 6 engage the ceiling, 65 and the roller 6 and the brush are rotated

by the handle. The roller 6 moves the container gradually along the ceiling and simultaneously applies cleaning fluid thereto and the brush renders a thorough scrubbing action on the ceiling so as to thoroughly 70 cleanse the same.

The set screw 24 provides means whereby the tension of the spring 26 can be varied by adjusting the cross arm 22 in the bracket 23.

While I have shown and described the 75 preferred embodiment of my invention, it will be understood that minor changes in construction, combination, and arrangement of parts may be made without departing from the spirit and scope of the invention 80 as claimed.

Having thus described my invention what I claim is:

1. A ceiling scrubbing machine comprising 85 a container, a fluid applying and scrubbing medium journaled in said casing, a supporting pole, arms journaled to the supporting pole and pivotally connected to the container, tension means for said arms for normally supporting said arms in an upwardly 90 inclined plane, operating means for the fluid applying and scrubbing medium, and a flexible element connected to the container for moving said container downwardly against the tension means. 95

2. A ceiling scrubbing machine comprising 100 a container, a scrubbing brush journaled in said container, a roller journaled in said container, means cooperating with said roller for preventing the container contacting with a ceiling, a supporting pole, yielding means connecting the container to the supporting pole and adapted to permit the container to move downwardly with relation to the supporting pole, flexible means 105 connected to said container for moving the same downwardly, an operating shaft slidably mounted on the pole and journaled to the container, means connecting the brush and roller together, and means connecting 110 the operating shaft to the last named means for imparting rotation to the roller and brush.

3. A ceiling scrubbing machine comprising 115 a container, a scrubbing brush journaled in said container, rollers journaled in said container and one of said rollers adapted to apply fluid to a ceiling, means for supporting the container, with the rollers and brush in engagement with the ceiling, means 120 for rotating one of the rollers and the brush to apply fluid to the ceiling with a scrubbing action and to cause the device to move along the ceiling.

4. A ceiling washing machine comprising 125 an open sided fluid container, a rotatable scrubbing means carried by the container, a supporting pole, a tension hinge connecting the pole to the container and adapted to permit the latter to be moved up- 130

wardly and downwardly relative to the pole, and means for rotating the scrubbing means.

5. A ceiling washing machine comprising an open sided fluid container, a roller in said container, a brush in said container, means rotatably and adjustably mounting the brush and roller in the container, means rotating the roller by the rotation of the brush, a supporting means for the container,

and an operating means carried by the supporting means for imparting rotation to the brush.

In testimony whereof I affix my signature in presence of two witnesses.

NILS J. SODERLUND.
